US0D1102439S

(12) United States Design Patent (10) Patent No.: US D1,102,439 S
 Duffy et al. (45) Date of Patent: * Nov. 18, 2025

(54) DISPLAY SCREEN OR PORTION THEREOF WITH A GRAPHICAL USER INTERFACE FOR PROSPECTIVE HOME BUYERS

(71) Applicant: ListReports, Inc., Orange, CA (US)

(72) Inventors: Matthew Kirkpatrick Duffy, Nashville, TN (US); Ajay Vinod Shah, Orange, CA (US); Randolph Vernon Shiozaki, Chino Hills, CA (US); David Duane Elkins, Irvine, CA (US); Wessal Abdel Khader, Orange, CA (US); Wendy Lee Oldfield, Kirkland, WA (US); Esther Yang, Anaheim, CA (US); Ryan Terrigno, Anaheim, CA (US)

(73) Assignee: ListReports, Inc., Orange, CA (US)

() Term: 15 Years

(21) Appl. No.: 29/823,224

(22) Filed: Jan. 14, 2022

(51) LOC (15) Cl. 14-04

(52) U.S. Cl.

USPC D14/486; D14/492; D14/495

CLAIM

The ornamental design for a display screen or portion thereof with a graphical user interface for prospective home buyers as shown and described.

DESCRIPTION

The sole FIGURE is a front view showing a display screen or portion thereof with a graphical user interface for prospective home buyers.

The outermost broken lines in the sole FIGURE show a display screen or portion thereof and form no part of the claimed design.

1 Claim, 1 Drawing Sheet
